ONE PIECE DUAL EXHAUST MANIFOLD FOR INTERNAL COMBUSTION ENGINES

Joseph Paul Marx, Hartford, Wis.

Application July 20, 1954, Serial No. 444,581

11 Claims. (Cl. 123—122)

The invention relates to improvements in an exhaust manifold for internal combustion engines and is more particularly concerned with the novel construction and assembly of such a manifold.

The standard one-piece exhaust manifold on an internal combustion engine is, in most instances, provided with a heat riser to the carburetor. The provision of two exhausts, which is highly advantageous for several well-known reasons is now conventional in some V-8 internal combustion engines. There is at present a trend to remove the original one-piece exhaust manifold on an in line engine and to substitute in its place a pair of exhaust manifolds each to accommodate some to the cylinder exhaust ports and each having its own exhaust pipe, muffler and tail pipe. One such installation is shown in my Patent No. 2,667,151, granted January 26, 1954, wherein there is disclosed a two-piece exhaust manifold which retains the necessary heat riser for the carburetor. Certain types of in line internal combustion engines are not susceptible of such installation but instead it is advantageous to retain the entire original exhaust manifold, including its heat riser, and to modify it in a manner that will divide the manifold into two sections or portions, each having some of the exhaust ports in communication therewith and each having its own exhaust outlet, exhaust pipe, muffler, and tail pipe. It is therefore an object of the present invention to provide a one-piece dual-exhaust manifold.

Another object of the invention is to provide novel means to divide a conventional manifold into two sections.

Another object is to provide a simple, inexpensive and easily installed divided exhaust manifold.

Another object is to provide a novel partition for an exhaust manifold and novel means for easily and quickly mounting the partition in place securely.

With the foregoing and other objects in view which will appear as the description proceeds, the invention consists of certain novel features of construction, arrangement and combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purposes of facilitating an understanding of my invention, I have illustrated in the accompanying drawings a preferred embodiment thereof, from an inspection of which, when considered in connection with the following description, my invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is a side elevational view of an internal com-

2

bustion engine showing the novelly reconstructed exhaust manifold thereon.

Fig. 2 is a vertical sectional view taken substantially on line 2—2 of Fig. 1.

5 Fig. 3 is a horizontal sectional view taken substantially on line 3—3 of Fig. 2.

Fig. 4 is a vertical longitudinal sectional view taken substantially on line 4—4 of Fig. 2.

Referring particularly to Fig. 1 of the accompanying

10 drawings, 11 schematically illustrates a six cylinder, in line, internal combustion engine provided with the usual intake manifold 12 which is connected in the usual manner to a carburetor 13. The engine 11 is also provided with a substantially conventional exhaust manifold 14.

15 The exhaust manifold 14 is in communication, through exhaust inlet ports 16, with the interior of the engine and is provided with the usual exhaust port 17 to which is connected the conventional exhaust pipe 18, as by means of bolts 19 passed through abutting flanges 21. The exhaust manifold 14 also includes a surface, indicated at 22, upon which a heat riser 23 to the carburetor 13 is mounted. This surface 22 is provided, in the manner best illustrated in Fig. 2, with an opening 24 communicating with the exhaust manifold interior.

25 It is desired to reduce the volume of gases passing through the exhaust pipe 18 and thereby minimize the back pressure normal attendant to such exhaust. To this end, the manifold 14 is divided in a manner to be

30 described presently so as to provide two sections or portions 25 and 26 therein, each of which is in communication with some of the exhaust inlet ports 16. In the present disclosure there are three exhaust inlet ports 16 in communication with each portion of the exhaust manifold. The means provided for dividing the manifold into sections 25 and 26 is arranged substantially 35 midway the length of the manifold.

More specifically, the division of the exhaust manifold is effected by mounting, within said manifold, a partition plate or barrier 27, which plate preferably is inclined

40 downwardly so as to direct exhaust gases entering the manifold portion 26, in front of said partition, downwardly through a hole 28 cut in the bottom wall of exhaust manifold closely adjacent to the partition 27. The hole is aligned with a second exhaust pipe 29 which is 45 secured to the manifold 14 as by bolts passing through a flange 32 on the end of the exhaust pipe 29. The bolts 31 extend entirely through bosses 33 formed on the manifold and constitute means for securing the heat riser 23 in place thereon. A spacer block 34 is arranged between the flange 32 and the body of manifold 14.

Referring now more particularly to Figures 2 to 4 inclusive, the partition 27 consists of a substantially rectangular shaped plate which is inserted through the heat riser opening 24, after the riser has been removed

55 temporarily during assembly. The plate 27 carries an eye-bolt 35 which extends loosely through said plate and is provided on its threaded end with a pair of lock nuts 36. The exhaust manifold 14 is further modified by

60 tapping a hole in the bottom wall thereof adjacent to the exhaust pipe 29. This hole is adapted to receive there-through a bolt 37, which extends through the eye 38 of the eye-bolt 35 and is securely locked against displacement by a lock nut 39. After the bolt 37 has extended

65 through the eye 38 and securely locked in place, the lock nuts 36 are tightened on to the eye-bolt 35 to draw the plate 27 into the inclined position best illustrated in Figure 4 so that its upper and lower edges are seated firmly against the opposed inside walls of the exhaust manifold.

70 The instant structure is such that it is relatively simple and inexpensive to convert and install the conventional exhaust manifold of the character disclosed herein. An en-

gine equipped with the converted manifold will operate without the creation of the usual back pressures accompanying conventional installations. All that is necessary in order to convert the conventional exhaust manifold system to the present two-exhaust pipe system is to remove the exhaust manifold and separate the heat riser 23 therefrom. The hole 28 is then cut in the bottom of the exhaust manifold and the tap opening provided for the bolt 37. The partition plate 27 then is inserted, preferably through the heat riser opening 24, and secured in place, whereupon the heat riser is replaced and the second exhaust pipe 29 is secured by the heat riser bolts 31. Should the plate 27 not fit snugly, as will be the case in many instances owing to the rough interior surface of the exhaust manifold, any slight leakage between the two sections will serve to equalize the pressure between the two manifold sections 25 and 26 and will in no way interfere with the functioning of the exhaust manifold as a dual manifold having dual exhausts. As a matter of fact, such leakage, if any, will function to stabilize or equalize the pressures in the sections 25 and 26.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. An exhaust manifold comprising, in combination, a hollow elongated member having ports spaced along its length adapted to register with exhaust ports of an internal combustion engine, a heat riser integral with said member, a partition dividing the interior of said member into two portions each containing some of said ports, means to secure said partition in place, and said member having an exhaust outlet adjacent one end of and communicating with one of said portions and a second exhaust outlet adjacent the partition and communicating with the other portion.

2. An exhaust manifold of the character recited in claim 1, in which the means to secure the partition in place consists of an eye-bolt carried by said partition and a bolt in the manifold engaging the said eye-bolt.

3. An exhaust manifold of the character recited in claim 1, in which the means to secure the partition in place consists of an eye-bolt carried by said partition and a bolt in the manifold engaging said eye-bolt, and means engaging the eye bolt to draw the plate in place tightly.

4. In an internal combustion engine having a plurality of exhaust ports on one side of its cylinder block and a fuel carburetor, an exhaust manifold communicating with said exhaust ports, a heat riser on said manifold upon

which the carburetor is mounted, a partition in said manifold dividing its interior into two sections, and exhaust outlets in said manifold one communicating with each section.

5. In an internal combustion engine of the character recited in claim 4, in which the exhaust manifold is in one piece and the heat riser is integral therewith.

6. In an internal combustion engine of the character recited in claim 4, in which the partition consists of a plate secured in the interior of said manifold.

7. In an internal combustion engine of the character recited in claim 4, in which the manifold consists of an elongated hollow structure and the heat riser and partition are located substantially midway of its length.

8. In an internal combustion engine of the character recited in claim 4, in which the manifold has one of its exhaust outlets adjacent one of its ends and the other substantially midway between its ends.

9. In combination with a internal combustion engine having exhaust ports, an exhaust manifold having inlet ports spaced along its length adapted to register with the said exhaust ports, a heat riser on said manifold, a partition in said manifold dividing it into two sections each containing some of said inlet ports, and exhaust outlets in said manifold one communicating with each section.

10. An exhaust manifold comprising, in combination, a hollow elongated body having ports spaced along its length adapted to register with exhaust ports of an internal combustion engine, a partition dividing the interior of the body into two sections each containing some of said ports, means to secure said partition immovably in place which comprises an eye-bolt carried by said partition and a bolt in the manifold engaging said eye-bolt, and said body having exhaust outlets one communicating with each section.

11. An exhaust manifold comprising, in combination, a hollow elongated body having ports spaced along its length adapted to register with exhaust ports of an internal combustion engine, a partition dividing the interior of the body into two sections each containing some of said ports, an eye-bolt carried by said partition, a bolt in the manifold engaging said eye-bolt, means engaging the eye-bolt to draw the partition in place tightly, and said body having exhaust outlets one communicating with each section.
